UNITED STATES PATENT OFFICE.

CHARLES F. MUELLER, OF ELIZABETH, NEW JERSEY.

SQUARE-HEAD NAIL-SET.

1,067,832.

Specification of Letters Patent.

Patented July 22, 1913.

Application filed May 24, 1911. Serial No. 629,199.

To all whom it may concern:

Be it known that I, CHARLES F. MUELLER, a citizen of the United States, residing at Elizabeth, in the county of Union and State 5 of New Jersey, have invented a new and useful Square-Head Nail-Set, of which the following is a specification.

It is one of the objects of the present invention, to provide a nail set which, when 10 laid upon a support, will not roll about.

A further object of the invention is to provide a nail set both ends of which are harder than the intermediate portion of the set, and to provide a protecting shield, for 15 the percussive end of the set, which shield is softer than the hardened, percussive end of the tool.

A further object of the invention is to provide, for the hardened, percussive end of 20 a nail set, a polygonal sleeve, constituting a means for preventing the set from rolling about upon a support.

With the foregoing and other objects in view which will appear as the description 25 proceeds, the invention resides in the combination and arrangement of parts and in the details of construction hereinafter described and claimed, it being understood that changes in the precise embodiment of 30 invention herein disclosed can be made within the scope of what is claimed without departing from the spirit of the invention.

In the accompanying drawings,—Figure 1 shows the invention in perspective; Fig. 2 35 is a longitudinal section; and Fig. 3 is an elevation, the constituent parts of the set being separated.

The set comprises an intermediate portion or body 1, knurled, or milled, as shown 40 at 2, the body 1 merging into a tapering tip 3, having in its end, the usual depression 4, adapted to receive the head of the nail. The opposite end of the body 1 is formed with a reduced spindle 5, defining a shoulder 6 in the set.

The tip 3 and the spindle 5 are tempered or hardened to a greater degree than the body portion 1, the elements 3 and 5 ordinarily being tempered by a special process, 50 or otherwise, to a violet blue. Over the spindle 5 is slipped, with a close driving fit, a sleeve 7, the sleeve 7 abutting against the shoulder 6. The outer end of the sleeve 7 is flush with the end face 8 of the spindle 5, the face 8 representing the percussive end 55 of the tool. The sleeve 7, adjacent the end

face 8 is tapered, as shown at 9, to expose the end face 8 prominently, to receive the blows of the hammer.

As denoted by the numeral 10, the sleeve 60 7 is of polygonal transverse section, the flat faces of the sleeve 7 outstanding beyond all other portions of the tool, as most clearly discernible in Fig. 2. The sleeve 7 is of softer material than the hardened spindle 5 65 which it surrounds.

When the nail set hereinbefore described, is laid upon a supporting surface, it will be seen that the flat faces 10, engaging such surface, serve to prevent the nail set from 70 rolling about. The nail set is the more effectively prevented from rolling about, for the reason that the faces 10 of the sleeve 7 are located beyond all other portions of the tool. The hardened spindle 5 is well adapted 75 to receive the blows of the hammer, and this spindle 5 is reinforced and strengthened, by the surrounding sleeve 7, which sleeve 7 is softer than the tempered or hardened spindle 5. The spindle 5, being hardened, is well adapted to stand the percussive 80 blows of the hammer, a cracking of this spindle 5 being prevented, by the surrounding sleeve 7 which, being softer than the spindle 5, possesses a greater tensile strength. 85

Owing to the beveling or tapering of the sleeve 7, as shown at 9, the end face 8 of the spindle 5 is exposed prominently to the hammer, and there will be no appreciable battering of the periphery of the sleeve 7, 90 adjacent its outer end.

Obviously, the shoulder 6 formed at the line of union between the spindle 5 and the body 1, constitutes a support, against which the sleeve 7 abuts.

For convenience, I have described the invention in the form of a nail set, but it is obvious that the essential principles of the invention may be embodied in prick punches, solid punches, center punches, and 100 in any other similar tool, the selection of a nail set being merely for the sake of presenting one embodiment of the invention.

Having thus described the invention, what is claimed is:—

1. A driven tool comprising a metal body; and a metal sleeve surrounding one terminal of the body; the terminal having greater compressive strength than the sleeve, and the sleeve having greater tensile 110 strength than the terminal.
2. A driven tool comprising a metal body;

and a metal sleeve surrounding one terminal of the body; the terminal having greater compressive strength than the sleeve, and the sleeve having greater tensile strength than the terminal; the sleeve being tapered to expose the end face of the terminal prominently.

3. A driven tool comprising a metal body have one of its terminals harder than its intermediate portion; and a metal sleeve surrounding one terminal of the body; the

terminal having greater compressive strength than the sleeve, and the sleeve having greater tensile strength than the terminal.

In testimony that I claim the foregoing ¹⁵ as my own, I have hereto affixed my signature in the presence of two witnesses.

CHARLES F. MUELLER.
